UNITED STATES PATENT OFFICE.

EDWIN H. PORTER AND BURLEIGH CURRIER, OF PHILADELPHIA, PENNSYLVANIA.

PUNCHING-MACHINE.

No. 806,362.

Specification of Letters Patent.

Patented Dec. 5, 1905.

Application filed March 29, 1905. Serial No. 252,614.

To all whom it may concern:

Be it known that we, EDWIN H. PORTER and BURLEIGH CURRIER, citizens of the United States, residing at Philadelphia, in the county 5 of Philadelphia and State of Pennsylvania, have invented certain new and useful Improvements in Punching-Machines, of which the following is a specification.

Our invention relates to improvements in 10 punching machinery; and the object of our invention is to produce a machine for cutting sheet-metal plates and forming them into disks or rings and at the same operation form notches in either the inner or outer edges of 15 the same.

A further object of our invention is to produce a punching-machine which is particularly adapted to making rings for laminations for electrical machinery at a minimum of 20 labor and to do so rapidly and more accurately than heretofore and at a greater reduction in the cost of production and also the cost of the dies and punches used in this class of machinery.

25 Our invention consists of a punching-machine having a work-table made of a plurality of sections and means for rotating said sections simultaneously by a step-by-step movement in conjunction with the operations of the 30 punches, together with various novel features of construction and organization of parts, which will be hereinafter more fully set forth and claimed.

Referring to the accompanying drawings, 35 Figure 1 is a plan view of our improved punching-machine. Fig. 2 is a vertical section as on line 2 2, Fig. 1. Fig. 3 is an end view taken from the right-hand end of Fig. 1. Fig. 4 is a partial vertical section, on a larger 40 scale, similar to Fig. 2, illustrating in diagram the electrical connections. Fig. 5 is a diagrammatic view of a sheet of metal, illustrating different designs into which the rings may be formed. Fig. 6 is a diagrammatic 45 view of the collector rings, brushes, and connecting-circuits supplying current for the magnetizing-coils.

In the drawings, A represents the bed-plate of the machine, having suitable supports *a* 50 and an upright bearing B and also a bearing C in the form of an arch extending over the center of the bed and from one side to the other of the same. In the bearings B and C is mounted a shaft D, driven by the driving-

shaft D' through the medium of the gear-wheel *d* and the pinion *d'*. Upon the shaft D are eccentrics E and E', having connecting-rods *e* and *e'*, carrying a cross-head F, guided at either end by guideways *f* and *f'* in the bearings C and B. Upon the cross-head F 60 are secured the punches G in suitable stocks *g*.

The upper surface of the bed-plate A is provided with annular grooves A', each of which is adapted to receive the annular projection H on the under side of each section H', 65 forming the work-table H². (More clearly shown in Fig. 4.) The sections H' of the work-table are each provided upon their outer periphery with ratchet-teeth *h*, which are engaged by a pawl I, pivoted to an arm I', located 70 below the sections H'. The said arm is pivoted at *i* to the bed A and is vibrated by a connecting-rod J, attached to the outer end of the arm at one end and at the other end to a crank J' on a rock-shaft J², having at its 75 opposite end a crank J³, which is connected by a rod J⁴ to a crank-pin J⁵ on the end of the shaft D. The ratchet-teeth on the different sections H' are so proportioned that a movement of the arm I' will cause all said sections 80 to rotate simultaneously.

The bed-plate A is provided with apertures A² to receive the dies G', which are located directly below the punches G.

The sections H' of the work-table are provided with circular grooves *h'* and *h²*, into which is coiled insulated copper wire H². Said grooves are covered by a circular plate or ring *h³*. In Fig. 4 the method of connecting the coils H² is shown, but any desired 90 method may be employed. Collector rings and brushes may be inserted between the different sections H', as indicated at *h⁴*, Fig. 6, to connect said coils. The coils are supplied with a direct current from any suitable source 95 to magnetize the sections of the work-table and hold the metal plate which is to be punched securely in contact with said work-table.

Having thus described our invention, we claim and desire to secure by Letters Patent— 100

1. The combination in a punching-machine of a circular work-table, means for rotating said work-table, a punch and die located on each side of said work-table and means for operating the same, substantially as described. 105

2. The combination in a punching-machine, of a work-table formed of a plurality of circular sections, means of rotating said sections,

a punch and die located between said sections and means for operating the same, substantially as described.

3. The combination in a punching-machine, 5 of a work-table formed of a plurality of independent circular sections, a pair of dies and punches located one at either side of each of said circular sections, means for operating said dies and punches and of advancing said 10 circular sections at every operation of said dies and punches, substantially as described.

4. The combination in a punching-machine, 15 for the manufacture of circular sheet-iron laminations for electrical machinery of a circular work-table arranged to revolve between a pair of dies, a pair of punches arranged to coöperate with said dies, the whole arranged and operated to successively punch out small 20 segments of circles of different radii of a sheet of metal carried by said work-table, substantially as described.

5. The combination in a punching-machine for electric machine laminations, of a work-table composed of a plurality of concentric 25 revolving sections, a plurality of dies and punches operating between said sections, and means for holding a sheet of metal on said table, substantially as described.

6. The combination in a punching-machine 30 for electrical machine laminations, of a work-table composed of a plurality of concentric revolving sections, a plurality of dies and punches operating between said sections and magnetic means for holding a sheet of iron on 35 said work-table, substantially as described.

7. The combination in a punching-machine for electrical machine laminations, of a plurality of dies and punches operatively connected, circular concentric work-table sections 40 arranged between each pair of dies, magnetiz-

ing-coils embedded in said tables, and means for operating said work-table sections in conjunction with said punches and dies, substantially as described.

8. The combination in a punching-machine, 45 of a bed-plate, annular grooves formed in the upper surface of said bed-plate, a work-table consisting of a plurality of independent circular sections having projections adapted to fit into the said grooves formed in the said bed-plate, fixed dies located in said bed-plate, 50 punches to coöperate with said dies and means for operating said punches and said work-table sections in conjunction with each other, substantially as described.

9. The combination in a punching-machine, 55 of a bed-plate, a work-table composed of sections adapted to revolve upon said bed-plate, dies and their corresponding punches operating between said sections, a shaft and cams 60 for operating the said punches, an arm pivotally connected to said bed-plate and operated by said shaft, pawls on said arm, and teeth formed on said sections adapted to be engaged by said pawls, substantially as described.

10. The combination in a punching-machine 65 of a plurality of dies and punches, a work-table consisting of independent circular sections, a bed-plate supporting said sections, grooves formed in said sections and wires coiled in the 70 grooves in the said sections by which said sections may be magnetized, substantially as described.

In testimony whereof we affix our signatures in presence of two witnesses.

EDWIN H. PORTER.
BURLEIGH CURRIER.
